SHOE

John B. Reinhart and John B. Reinhart, Jr.,
 Kirkwood, and Albert C. Bollmann and Kenneth G. Schneider, St. Louis, Mo., assignors to Trimfoot Company, St. Louis, Mo., a corporation of Missouri

Application December 30, 1940, Serial No. 372,312

1 Claim. (Cl. 36—8.5)

This invention relates to high shoes, as distinguished from low cut shoes or oxfords. One inherent objectionable feature or characteristic of the conventional high shoe, is that the portion of the upper located above the counter or counter zone, has a tendency to wrinkle, break down and lose its shape, due to the fact that the leather from which the upper is constructed and the fabric that constitutes the inner lining of the shoe, are not stiff enough to successfully resist the strains to which this portion of the shoe is subjected in the normal use of the shoe. This not only detracts greatly from the appearance of the shoe, but it is also liable to cause or produce foot trouble, inasmuch as the wrinkled or crunched portion of the upper tends to force the user's foot forwardly, with the result that the user's toes are crowded too far forwardly into the toe portion of the shoe, and the user's heel is shifted forwardly off of the portion of the shoe sole on which the user's heel is intended to rest. The foregoing is true of all types and kinds of high shoes, irrespective of whether or not a substantially stiff member or counter is built into the portion of the shoe upper immediately adjacent the heel end or rear end portion of the shoe sole.

The main object of our invention is to provide a high shoe in which the portion of the upper located above the counter or the counter zone, is reinforced and strengthened in a novel manner that effectively prevents this portion of the upper from wrinkling, crunching, or assuming such a shape or form that the user's foot is liable to assume an improper position in the shoe.

Another object is to provide a high shoe that will support and hold the heel and toes of the user's foot in the position they are intended to occupy, and also have a sufficiently snug fit around the user's ankle to support the same and hold it rigid.

And still another object of our invention is to provide an inexpensive high shoe, which is of such construction that even after the shoe has been subjected to long or hard usage, the portion of the upper above the counter or the counter zone, will be free from wrinkles and maintained in snug engagement with the portion of the user's foot encased by same.

The invention is applicable to various types and styles of high shoes, constructed from various kinds of materials, and equipped with various types and kinds of soles. We have herein illustrated the invention applied to a child's high

shoe of the blucher type whose upper extends above the user's ankle, but we wish it to be understood that the invention is also applicable to adult's high shoes.

5 Figure 1 of the drawing is a side elevational view of our improved shoe.

Figure 2 is a side elevational view, partly broken away so as to more clearly illustrate the reinforcing and strengthening member that is attached to the inner lining of the shoe; and

Figure 3 is a perspective view illustrating the general shape or form of said re-inforcing and strengthening member.

15 In the drawing, A designates as an entirety the upper of a high shoe, and B designates the sole of said shoe. Our invention consists in equipping a high shoe with an upper re-inforcing device C of the general shape or design shown in Figure 3, arranged on the interior of the shoe and extending continuously or unbrokenly from the sole of the shoe to the top edge of the upper, so as to prevent the portion of the upper located above the counter or the counter zone, from wrinkling or breaking down. Preferably, 20 the reinforcing and strengthening member C is provided with two forwardly-projecting arms that draw the top edge of the upper snugly around the user's foot and exert a forward pull on the counter or counter zone of the shoe, with the result that the rear end portion of the shoe will conform accurately to the shape of the user's foot, and the portion of the upper located above the counter or counter zone will be prevented effectively from wrinkling, breaking down, or losing 25 its shape when the shoe is in use.

Usually the member C will be formed of leather and arranged on the interior of the shoe in superimposed relation with the shoe lining, said member C being attached at its bottom edge by 30 stitches, or in any other suitable way, to the sole of the shoe, as shown in Figure 2. The other marginal edges of the member C are permanently fastened by stitches x to the upper or to the lining of the shoe. However, the particular material of which the member C is formed and the particular way said member is built into the shoe are immaterial. We prefer to construct the member C from a single piece of leather or other suitable flexible sheet material, cut or designed 35 so that it comprises a lower portion of the approximate shape or outline of a conventional shoe counter, an upper portion that constitutes a horizontally-disposed band around the top edge of the shoe upper, and an integral intermediate web that joins said top and bottom portions to

gether. As shown in the drawing, the bottom portion of the member C, which is attached to the sole portion of the shoe, is of substantial height and extends forwardly to a point adjacent the breast line of the heel or heel portion of the shoe sole B. Said counter-shaped bottom portion embraces or surrounds the heel seat portion of the sole, and it projects upwardly a considerable height before merging into the web portion of the member C that extends upwardly at the rear side of the shoe upper. When the shoe is in use, the forwardly projecting arms 1 of the member C that are stitched or otherwise securely attached to the top edge portion of the shoe upper, co-operate with the vertically-disposed web and the counter-shaped lower portion of the member C to produce a re-inforcing and strengthening device, which not only insures that the shoe will snugly fit the user's foot, but which has the added desirable characteristics of preventing the user's socks from wrinkling and preventing the user's toes from being crowded forwardly into the toe portion of the shoe, due to breaking down of the portion of the shoe upper located above the counter zone of the shoe. If the shoe is provided with a conventional stiff counter and a fabric inner lining, the member C is preferably superimposed on said inner lining, so that it constitutes part of the exposed inner surface of the shoe, the lower portion of the member C co-operating with the shoe upper to form a housing or pocket for the stiff counter. Obviously, the fabric inner lining of the shoe may be omitted, without departing from the spirit of my invention. In certain types of shoes, 35 for example, baby shoes, it is not necessary to employ a stiff counter, inasmuch as the member

C, after being attached to the sole and to the upper of the shoe, imparts sufficient strength or stiffness to the portion of the upper located above the counter zone, to maintain the original 5 shape or form of this portion of the upper and prevent it from crunching under the strains to which this portion of the upper is subjected when the shoe is in use.

Having thus described our invention, what we 10 claim as new and desire to secure by Letters Patent is:

A high shoe provided with an upper that extends upwardly above the user's ankle, and a re-inforcing and strengthening member of non- 15 elastic, pliable material arranged at the rear end of the shoe on the interior of same, so as to constitute part of the inner surface of the shoe, said re-inforcing and strengthening member comprising the following parts: (1) a bottom 20 portion of approximately the shape or outline of a conventional shoe counter, attached to the sole portion of the shoe in the zone of the heel seat and terminating at its front end adjacent the breast line of the shoe heel; (2) a top portion 25 extending continuously around and secured to the top edge portion of the upper of the shoe; and (3) a vertically-disposed web portion integrally connected to said top and bottom portions and co-operating with the same to prevent wrinkling or breaking down of the portion of the shoe upper located above the counter zone of the shoe.
